MANIFOLDING MACHINE

Milton C. Stern and Frank E. Pfeiffer, Dayton,
Ohio, assignors to The Egry Register Company,
Dayton, Ohio, a Corporation of Ohio

Application January 16, 1931. Serial No. 509,057

7 Claims. (Cl. 282—12)

Our invention relates to manifolding machines.

It is the object of our invention to provide a machine for making a plurality of copies either 5 by hand or by machine.

In particular it is our object to make such copies which are initially printed on a single piece of paper and fan folded, are then split into a plurality of sheets and can be ejected as independent pieces of paper with duplicate autographic or machine made records on them.

It is our object to provide a mechanism which will separate the several sheets of the fan folded piece of paper without any refuse being deposited 10 in the machine, maintain the separate sheets in interleaved condition between carbon sheets without injuring the edges of the carbon sheets, maintain those sheets in alignment, and provide a ready means of withdrawing the sheets as well 20 as holding the sheets during the writing operation.

It is another object of our invention to provide a very shallow flat means for accomplishing the foregoing which may lay on top of a 25 table or counter or form a part of a counter, thus obviating the present difficulties in large machines for recording transactions, such as autographic registers, cash registers, tabulating and computing machines.

In particular, it is our object to provide a flat table mechanism of the character described 30 which may form the top of a table or stand and with which the stationery can be stored at some remote point where it can be conveniently located.

It is our object to provide a machine in which the transactions may be put in by hand or a flat bed typewriting or tabulating machine may 35 be placed over the writing opening and the record made mechanically. When rush seasons occur in business, it is frequently necessary to go to great expense to rent additional tabulating machines, but, with an apparatus of this sort, this is not necessary as the entries can be made 40 by hand if desired.

When the machine of our invention is not in use, the writing opening can be closed with a cover so that the entire machine presents the appearance of a table or counter top over which 45 other transactions can be conducted.

Referring to the drawings:

Figure 1 is a top plan view of our machine with the cover for the writing opening in open position;

Figure 2 is a side elevation;

Figure 3 is a top plan view with the sheets in position and the cover removed;

Figure 4 is a top plan view with the sheets removed;

Figure 5 is an enlarged detail view showing the 60 arrangement of the cutters in connection with the sheets;

Figure 6 is a section on the line 6—6 of Figure 5;

Figure 7 is a section on the line 7—7 of Figure 5;

Figure 8 is a section on the line 8—8 of Figure 5; and

Figure 9 is a section on the line 9—9 of Figure 5. 70

Referring to the drawings in detail, 1 is a frame support of wood or metal having a suitable recess for the accommodation of the guiding and slitting mechanism and for the carbon roll storage as well as the plurality of paper 75 sheets passing from the supply and out through the ejector.

This recess is designated generally as 2. The stack of fan folded sheets in unslit condition is usually located in a remote container as at 3. 80 This stationery consists of a single sheet folded with a series of superimposed folds as at 4, each fold of the main sheet being designated as 4a—b—c—d and e. This sheet in folded unslit condition is fed into the machine of our invention 85 beneath the guides 5 over the rollers 6.

Between the lowermost sheet and the next one above it are inserted the cutting disks 7 which are pivotally supported at 8 upon the angular brackets 9 fastened to the frame 1 within the depression 2. The next sheets above are guided by the guide members 10 which are similar to the guides 5 and they in turn are separated by the interposed cutting disks 11 pivoted at 12 95 on the angular brackets 13 mounted at 14. The single sheet is thereby separated into a plurality of superimposed sheets, in this instance five in number, which are fed between the transverse bars 13a mounted on the studs 14a. Each of 100 these bars carries a pair of linen sheets 15 which overlap the top and bottom of the respective carbon sheets 16 between which the sheets 4b—c—d and e are inserted and over which sheet 4a passes.

The forward ends of these sheets are clamped by the clamp 17 which holds them in writing position. This clamp may be elevated, when desired, through rocking the finger piece 18 which has connected to it the lever 19 which, 110

in turn, engages the plunger 20 which moves the clamp 17 upwardly against the resistance of the spring 21.

The carbon sheets are supplied from a roll of 5 sheets 22 carried on the roll support 23 in a carbon supply box 24 in the frame 1. When it is desired to pull the sheets outwardly, the free ends of the sheets are grasped after lifting the clamp 17, pulled the requisite distance and then 10 torn off against the clamping bar 17. If it is desired to measure the length of pulling out the sheets, the end of the measuring bar 25 may be 15 grasped with the sheets and the sheets pulled out until the end of the slot 26 of the measuring bar 25 engages the stud 27^a to limit its movement. That indicates the limit to which the sheets should be pulled outwardly before being torn off.

Over these sheets and the mechanism for 20 handling the sheets is mounted the hinged lid 27 hinged to the frame 1 at 28 and having a writing opening 29. This opening in turn has a cover 30 hinged thereto which can be used to cover the writing opening 29 when the machine is inoperative and it is desired to use the 25 entire upper surface as a table or counter.

It will be observed that an autographic entry 30 can be made on the several superimposed sheets, or the machine of our invention can take the place of a flat platen of a mechanical writing machine, such as a typewriter, calculator, book-keeping machine, and the like.

It will be further noted by using the interleaved cutting disks that all the refuse, known 35 as confetti, is eliminated because the cut between the sheets is a clean cut and it is not a cut against a transverse bar which serves to leave the sheets ragged and discharge small pieces. Such refuse soon collects on the machine 40 and between the sheets and prevents perfect, easy and smooth operation.

The guides 5 and 10 maintain the sheets in 45 position. The linen guards protect the carbon sheets so that the interleaved paper sheets pass freely between them.

One of the marked advantages of our invention is that it is very shallow, that it can be formed as a part of a counter or desk, that it is adaptable to either machine or handwriting, 50 that the bulky stationery may be stored at a distance where space is not at a premium, and all obstructions to work on the counter or desk are removed such as heretofore have existed with permanently attached machines, autographic registers, cash registers, tabulating machines, and the like.

The further and principal advantage is that 60 stationery, which is printed in a single sheet and therefore of the same kind of paper and printed at the same time with corresponding accuracy of registration, can be delivered through a machine, neatly severed into several sheets as desired without severing the portion that is not being used and thereby be able to eject a plurality of independent pieces of paper which are 65 perfect copies one of the other and in perfect registration. The difficulty with having pre-cut, superimposed sheets is that they must be printed at different times with differences often in 70 the paper causing differences in printing and registration and with different supplies of this character it requires considerable bulk of storage and difficulty in maintaining alignment, but, by using a source of supply as in the present 75 case of one piece of paper, the severed ends of

the sheets of paper, which are being written upon, cannot shift bodily and get the entire sheet out of registration, as the sheet is maintained in its integrity as a single piece of paper until shortly before writing upon it, and, even then, it is still connected to the main sheet of unsevered paper. Hence, all that there is to do for aligning purposes is to hold the free ends of the sheet firmly during the writing operation.

It will be understood that we desire to comprehend within our invention such modifications as may be necessary to adapt it to varying conditions and uses.

Having thus fully described our invention, what we claim as new and desire to secure by Letters Patent, is:

1. In a machine for making multiple records, means including a frame having a recess therein for guiding a fan-folded sheet of a single piece of paper into the machine, means in the recess of severing the connection of the superimposed portions of the sheet at one end thereof from one another while the inner ends thereof are still connected to the unsevered portion of the sheet, means for guiding a plurality of carbon leaves therebetween, and manually operated means for clamping the free ends of the sheets beyond the carbon leaves, and a cover with a writing opening adapted to enclose said sheets and maintain them in writing position. 100

2. In a machine for making multiple records, means including a frame having a recess therein for guiding a fan-folded sheet of a single piece of paper into the machine, means in the recess of severing the connection of the superimposed portions of the sheet at one end thereof from one another while the inner ends thereof are still connected to the unsevered portion of the sheet, means for guiding a plurality of carbon leaves therebetween, and manually operated means for clamping the free ends of the sheets beyond the carbon leaves, and a cover with a writing opening adapted to enclose said sheets and maintain them in writing position. 110

3. In an apparatus for making duplicate records, a frame having a recess in its upper surface and an opening through the frame at one end of the recess for the passing of sheets of paper into the recess, guides for the sheets of paper on each side of the recess projecting over the edges of the sheets, and a roller in the opening for guiding the sheets into the recess. 125

4. In an apparatus for making duplicate records, a frame having a recess in its upper surface and an opening through the frame at one end of the recess for the passing of sheets of paper into the recess, a guide roller in the opening for guiding the sheets into the recess, and means extending across the recess at the other end thereof for clamping the sheets. 135

5. In an apparatus for making duplicate records, a frame having a recess in its upper surface and an opening through the frame at one end of the recess for the passing of sheets of paper into the recess, a guide roller in the opening for guiding the sheets into the recess, and means extending across the recess at the other end thereof for clamping the sheets, said means consisting of a transverse bar having at each end means to hold it against the sheets. 140

6. In an apparatus for making duplicate records, a frame having a recess in its upper sur- 150

face and an opening through the frame at one end of the recess for the passing of sheets of paper into the recess, a guide roller in the opening for guiding the sheets into the recess, and means extending across the recess at the other end thereof for clamping the sheets, said means consisting of a transverse bar having at each end a plunger passing through the frame and means engaging the plungers to hold the bar against the sheets.

7. In an apparatus for making duplicate rec-

ords, a frame having a recess in its upper surface extending from one end to a point adjacent the other end and terminating in an opening through the bottom of the frame, a roller in the opening for guiding sheets into the recess, and a clamp bar across the recess for clamping the sheets therein, one edge of said bar being beveled to form a tearing edge.
